UNITED STATES PATENT OFFICE.

ALONZO BADGER, OF OCEANPARK, CALIFORNIA, ASSIGNEE OF ONE-HALF TO
HENRETTA TUNZAT, OF OCEANPARK, CALIFORNIA.

LIFE-PRESERVING SWIMMING-JACKET.

961,282.

Specification of Letters Patent. Patented June 14, 1910.

Application filed February 21, 1910. Serial No. 545,177.

To all whom it may concern:

Be it known that I, ALONZO BADGER, a citizen of the United States, residing at Oceanpark, in the county of Los Angeles and State of California, have invented a new and useful Life-Preserving Swimming-Jacket, of which the following is a specification.

It is the object of this invention to provide in a merchantable, inexpensive and compact form, a garment so constructed that it may readily be donned, and inflated, to serve as a life-preserved, so called.

Another object of the invention is to provide a device of the class above mentioned which shall house securely against accidental injury the buoyant element of the device.

Another object of the invention is to dispose the buoyant element of the device in a novel and improved form, in which its efficiency will be increased.

Another object of the invention is to strengthen the device at the point where the valve of the inflatable element protrudes through the vest portion of the device, and to house the valve.

With the above and other objects in view, the invention consists in the novel construction and arrangement of parts hereinafter described, delineated in the drawings, and specifically claimed, it being understood that changes, properly falling within the scope of what is claimed, may be made, without departing from the spirit of the invention.

Similar numerals of reference are employed to denote corresponding parts throughout the several figures of the drawings.

In the accompanying drawings,—Figure 1 is a plan of my device, the same being laid flat, to expose the exterior surface thereof; Fig. 2 is a perspective showing the front portion of the device, as applied; Fig. 3 is a fragmental transverse section of the device, taken in the vicinity of the valve of the inflatable member, parts being shown in elevation; Fig. 4 is a perspective showing the rear portion of the device, as applied; and Fig. 5 is a fragmental plan, upon an enlarged scale, designed to show with particularity, that portion of the device through which the valve of the inflatable element protrudes.

The structure in which my invention is,

in the present instance, embodied, comprises, as a fundamental element, a vest, which in Fig. 1 of the drawings, is denoted generally by the numeral 1. Along the end edges of this vest 1, there are reinforcing strips 2, one of which is provided with a plurality of outstanding tongues 3, the other of which is provided with buckles 4 adapted to receive the tongues 3, whereby the vest may be secured about the body of the wearer. Upon its lower edge, and at the back, the vest 1 is split and overlapped, as denoted by the numeral 5, to reinforce the vest at that point.

The vest may be fashioned of any desired material, and in any desired manner. In the present instance, it consists of an inner layer 6, and an outer layer 7, between which is disposed the buoyant, inflatable portion of the device. This buoyant element consists, in the present instance, of a flexible tube having its ends 8 closed, and disposed upon the front of the vest 1, adjacent the upper edge of the vest. Thence, the inflatable element is extended beneath the arm-holes of the vest, as denoted by the numeral 9, and bent somewhat sharply upon itself in its intermediate portion, as shown at 10. This intermediate portion 10 is secured between the arm-holes of the vest, at the back thereof, and adjacent the upper edge of the vest, the preferred means for securing the inflatable element in place, being two lines of stitching 11, securing the layers 6 and 7 together.

The arm-holes of the vest are defined by the straps 12. These straps 12, like the vest proper, are multi-layer structures, one layer of which at its end is secured as denoted by the numeral 14, between the layers 6 and 7 of the vest, at the rear thereof, the end of the other layer, as shown at 15, being extended upon the exterior of the layer 7 of the vest.

The bent intermediate portion 10 of the inflatable tube is provided with a valve 17, and this valve, as clearly shown in Fig. 3, protrudes through the outer layer 7 of the vest. In order that the free end of the valve 17 may not come into contact with the body of the wearer of the device, the body portion of the vest, at its back, is upwardly extended as shown at 16, between the diverging straps 12. In order to house the valve 17, with the exception of its extremity, a patch 18 is

2

mounted transversely upon the back of the vest adjacent the upper edge of the vest. This patch 18 is extended laterally to overlie the ends of the straps 12, and when the 5 several parts are secured together by stitching, or other common means, it will be seen that this patch 18 constitutes, at once, a housing for the valve 17, and a means for securing the ends of the straps 12 upon the 10 vest.

In practical operation, the vest is worn in the usual manner, as shown in Figs. 2 and 4, the garment being secured across the chest of the wearer by means of the buckle 4 and the 15 tongue 3. Previous to putting on the vest, a common bicycle pump or the like is connected with the valve 17, and the tube is inflated, so that the same will cause the outer layer 7 to outstand slightly, as shown in Figs. 20 2 and 4, the tube nevertheless being adequately protected by the layers between which it is mounted, against accidental injury. When the device is in position, there will be an air reservoir extending, as shown 25 at 20 in Fig. 2, in diverging lines across the chest of the wearer, and thence beneath his arms, to form the V shaped portion 19 terminating between the shoulder blades, as shown in Fig. 4.

30 Owing to the peculiar disposition given to the inflatable element, it will be seen that it will be impossible for the wearer thereof to assume a position in the water in which the entire device will be above the surface.

35 Thus, if he is swimming upon his back, the V shaped portion 19 will be immersed, and if he is swimming upon his side, one of the portions which are disposed beneath the arm-holes of the vest will be immersed.

40 Likewise, when he is swimming upon his chest, the portion 20 will be immersed, and should he be standing upright, the entire device will be effective as a buoyant structure. The inflatable tube, which is the most 45 delicate portion of the structure, is, as will be clearly seen from the drawings, securely housed between the constituent layers of the vest, unusual protection being given to that portion of the tube from which the valve 17 50 protrudes.

The construction of the device is such that

it may readily be deflated at will, and may be readily inserted in a grip sack or trunk, taking up no more room than an ordinary garment.

Having thus described the invention, what is claimed is:—

1. A device of the class described comprising a vest having arm-holes, and securing devices upon its end edges; and a buoyant 60 member extended beneath the arm-holes and having its ends prolonged up the front of the vest to points adjacent the upper edges thereof, the buoyant member being bent upon itself intermediate its ends, and having 65 its bent portion secured between the arm-holes upon the back of the vest, adjacent the upper edge thereof.

2. A device of the class described comprising a multi-layer vest having arm-holes; an 70 inflatable tube disposed between the constituent layers of the vest and extended beneath the arm-holes, the tube having its ends prolonged up the front of the vest to points adjacent the upper edge thereof, and having 75 its intermediate portion sharply bent and disposed between the arm-holes upon the back of the vest, adjacent the upper edge thereof; and a valve located in the intermediate portion of the tube and arranged to 80 protrude upon the exterior of the vest.

3. A device of the class described comprising a multi-layer vest having an inflatable element disposed between its constituent layers at the back of the vest and adjacent its 85 upper edge; straps defining the arm-holes in the vest, and secured to the back thereof; a valve protruding from the inflatable element through the outer layer of the vest, the vest being prolonged between the straps to receive the free end of the valve; and a patch 90 secured to the vest and constituting at once a housing for the valve, and a means for securing the strap ends.

In testimony that I claim the foregoing as 95 my own, I have hereto affixed my signature in the presence of two witnesses.

ALONZO BADGER.
